Primary Examiner — Ian Simmons*Assistant Examiner* — Keith Frank(74) *Attorney, Agent, or Firm* — The Belles Group, P.C.(57) **CLAIM**

The ornamental design for a bottle, as shown and described.

DESCRIPTION

FIG. 1 is a perspective view of a bottle showing my new design;

FIG. 2 is a front side elevation view thereof;

FIG. 3 is a right side elevation view thereof;

FIG. 4 is a top plan view thereof; and,

FIG. 5 is a bottom plan view thereof.

The rear side of the design is a mirror image of the front side, and the left side of the design is a mirror image of the right side.

The broken lines in the drawings illustrate the portions of the bottle that form no part of the claimed design.
